UNITED STATES PATENT OFFICE.

HEINRICH BANDMANN, OF OBERDISTELN, GERMANY.

TURN-TABLE.

No. 832,650.

Specification of Letters Patent.

Patented Oct. 9, 1906.

Application filed June 25, 1906. Serial No. 323,202.

To all whom it may concern:

Be it known that I, HEINRICH BANDMANN, a citizen of the German Empire, and a resident of Oberdisteln, Westphalia, Germany, have invented certain new and useful Improvements in Turn-Tables, of which the following is a specification.

The invention has for its object a turn-plate for track-crossings as used for tracks of small gage, principally for field and mine lines, to replace the separately-built-in turn-table for turning the vehicles and forming branch connections.

The invention is characterised by the fact that the turn-plate is not, as hitherto, built in in such a way that its surface lies below the top of the rails, so that the flanges of the wheels are able to run directly on the plate, which, however, necessitates an interruption 20 of the track where the turn-table is built in.

In accordance with the present invention the plate is simply laid upon the continuous track and the possibility of the vehicle running onto the turn-plate without shock or excessive effort is afforded, owing to the fact that this plate is provided with deflected or bent parts lying between the rails and corresponding as exactly as possible to the gage. These bent parts serve as inclined 30 planes upon which the flanges of the wheels run and by means of which the vehicle is brought onto the surface of the turn-plate. This surface is situated above the top of the rails by the amount of the thickness of the 35 plate. The vehicle runs off the plate on the other side in a precisely similar manner. The bent parts engaging between the rails likewise prevent the rotation of the plate when the vehicle is being turned. Accordingly the novel turn-plate may be placed on 40 any part of a continuous track for the purpose of forming a level crossing without any preparation. The lateral connecting track or the two branch tracks may be arranged against 45 the turn-plate in such a manner that they ascend toward it, thus causing the top of their rails to extend so far above the surface of the turn-plate that the flanges of the vehicle traveling onto the connecting tracks run 50 directly upon the plate. Another method of effecting these lateral connections consists in forming not only the ends of the turn-plate which lie between the rails of the through-track as inclined planes, but also providing 55 the ends of the plate lying between the rails of the branches with an inclined bearing-surface

for the flanges of the wheels. The turn-plate is then perfectly symmetrical, so that the tracks may all lie in one plane.

The turn-plate is provided in the middle in the known manner with a vertical pivot, serving as a stop when a vehicle is turned, the diameter of this pivot being approximately equal to the gage less twice the thickness of the flange. Guiding-angles provided with rounded-off corners and placed at each crossing serve to insure the guidance of the vehicle onto the track.

In the accompanying drawings a constructional form of the device in accordance with the invention is shown, the formation being the same on all four sides.

Figure 1 is a perspective plan view; and Fig. 2 is a section on the line I I of Fig. 1, showing a mine-truck passing over it.

The through-track *b* rests upon the sleepers *a* and may be considered as the main line, and against it the branch or connecting lines *c* and *d* are arranged at the desired place in such a manner that the tops of all the rails lie in one plane. The turn-plate *e* is placed upon the level crossing formed in this manner. This plate is formed, mainly, by the central vertical pivot *f* and the plate members *h*, with guide-angles *g* chamfered off toward the rails. These parts *h* correspond in width to the gage and are bent downward, forming inclined planes which provide the necessary bearing for the flanges of the vehicle-wheels to run on, in order to conduct them onto the turn-plate without shock or excessive effort. The lower ends of the inclined plates *h* rest upon the feet of the rails. In order, however, to obtain the necessary stiffness with a comparatively small thickness of the plate, these ends are preferably bent so as to form a vertical web *i*. This arrangement prevents tilting of the plate around an axis passing through the supporting-surfaces when a vehicle runs onto and off the plate. In practice the symmetrical formation of the plate secures the still further advantage that when only one branch is used one-sided wear may be compensated for by turning the plate through ninety degrees after it has been in use for a certain time. Further, by this formation the branch tracks abutting obtusely against the through-track are held together and against the main track.

The turn-plate described is pressed out of ingot-iron, and the equal-sided formation is particularly adapted for this. In this con-

struction the pivot *f* and the guide-ledges *g* are pressed hollow; but they may of course be equally well formed as separate parts and be attached by riveting or otherwise. By 5 means of the inclined planes *h*, provided on all four sides, in combination with the bent-over webs or flanges *i*, the turn-plate is made very stiff, so that it is possible to use very thin sheet metal, notwithstanding the rough 10 treatment to which the plate may be subjected in use. The resulting lightness of the plate is an important advantage and facilitates its displacement.

Numerous modifications in the form of a 15 turn-plate of this kind may be introduced without departing from the principle, and the constructional form illustrated and described should only be regarded as an example to which the invention is in no way confined.

What I claim is—

1. Turn-plate for the formation of track branches or crossings, consisting of a plate to be laid upon the through-track with bent 25 portions in the form of inclined planes engaging between the rails, and connections for the branch tracks.

2. Turn-plate for the formation of track

branches or crossings, consisting of a plate intended to be laid upon the through-track 30 with bent portions in the form of inclined planes which engage both between the rails of the through-track and between the rails of the branch tracks which are arranged in the same plane as the former.

3. Turn-plate for the formation of track branches and crossings, consisting of a plate intended to be laid upon the through-track, with bent portions in the form of inclined planes 35 engaging between the rails, and webs 40 on the same which rest upon the feet of the rails.

4. Turn-plate for the formation of track branches and crossings, consisting of a plate intended to be laid on the through-track with 45 bent portions in the form of inclined planes engaging between the rails with a pivot serving as a stop when a vehicle is being turned and guiding-angles on the corners of the plate.

Signed by me at Düsseldorf, Germany, this 25th day of May, 1906.

HEINRICH BANDMANN.
